UNITED STATES PATENT OFFICE.

VIKTOR JERECZEK, OF LICHTENBERG, NEAR BERLIN, GERMANY, ASSIGNOR TO, SCHNELLPRESSENFABRIK AKTIENGESELLSCHAFT HEIDELBERG, OF HEIDELBERG, GERMANY, A CORPORATION OF GERMANY.

PRINTING PRESS.

Application filed May 20, 1924, Serial No. 714,695, and in Germany May 28, 1923.

My invention relates to printing presses; more especially it relates to an automatic feeding and discharging device for such presses, for instance platen printing presses.

5 I am aware of the fact that there exist devices of this kind, in which the grippers moving the work-piece, i. e. the printing sheet, swing or oscillate around an axis arranged vertically with respect to the plane 10 of that work-piece, but with those known devices difficulties were encountered in operating their grippers in such a manner that the work-pieces, or the printing-sheets respectively, were fed into the press, moved 15 forward therein, and discharged, in the proper manner. An especially difficult point was keeping the grippers checked in their end-positions, and a lot of interruptions of service resulted just from this cause. 20 Hitherto the grippers have been actuated by eccentrics, pawl-gears, and the like, which, however, gave rise to difficulties after a comparatively short duration of service even if they were of first-class make. Re- 25 source was taken to springs which were inserted into the respective driving means and the object of which was to force the actuating members proper into the required positions in spite of play and back-lash. But 30 just these springs caused new disturbances.

The object of my invention is to do away with these and other difficulties and to obtain a positive drive which is superior to the former drives, in that the grippers are caused 35 by very simple and reliable means to move exactly in the requisite manner and at the accurate point of time. An important point which must be observed is that the grippers must not move with uniform speed through 40 their path, but the speed must be accelerated gradually from zero to a certain maximum and must then be delayed gradually down to zero.

The gist of the invention consists, therefore, 45 therein that a driving member which rotates with uniform speed, engages, during every feed-movement of the grippers, a second rotating member at several points consecutively, viz, from the outer end in the 50 direction to the axis, and reversely, whereby the speed is accelerated gradually from zero to a maximum and from this down to

zero. This second rotating member is in connection with the grippers, which therefore, at every feed-movement, are driven 55 with varying speed.

It is suited to the purpose to arrange and combine the parts concerned in such a manner that the rotating driving member engages the driven part while the grippers perform their feeding movement, and that the driving part (pivot, roll, sliding block) is shifted radially or approximately radially along the driven part, whereby motion is imparted to the grippers only when, and only 65 as long as, it is necessary to move the work piece. In order to retain in every case the grippers in their position of rest, a checking device controlled by the press may be provided, this device acting on the driven 70 part of the grippers, as is all more fully described hereinafter.

My invention is illustrated diagrammatically and by way of example in the accompanying drawings in which Figure 1 is a 75 side-view of a part of the press with its platen, a few parts being shown in vertical section; Figure 2 is a vertical section taken on line I—I of Fig. 1, Figure 3 is a vertical section through the parts shown in the upper 80 part of the lefthand half of Fig. 1, in the plane of this Figure (1), the Figure (3) being drawn on an enlarged scale and showing the gear intended for the grippers and carried by the platen; and Figure 4 is a front- 85 view of the parts shown in Fig. 3.

In the frame 1 of the press is supported the main driving shaft 2 (Figs. 1 and 2) to which is affixed a disk 3 or another member carrying two rolls 4 which revolve with the 90 same speed as the shaft 2. Below this shaft is a shaft 5 also supported in the frame 1, and on it is fastened a disk 6 having a plurality of guide-ways 7. In the example shown there are four radial guide-ways 95 forming a cross. The arrangement of the rolls 4 relatively to said guide-ways is such that they engage them successively when revolving, whereby the disk 6 is partially rotated. This rotatory motion commences when 100 a roll enters into the adjacent guide-way, and the speed of this motion increases gradually as the roll moves towards the centre of the disk 6; it is greatest at the end of the path

of the respective roll in the respective guide-way, and then decreases down to zero while the roll moves away from that end outwards to the outer end of the respective guide-way.

5 That gradually accelerated and then gradually retarded motion is transmitted by the control disk 6 to the shaft 5 and by this to a pair of bevel-wheels 8, one of these wheels being affixed to the shaft 5 and the 10 other to a shaft 10, the other end of which is connected by a ball-joint 9 with an obliquely upwards extending shaft 10^a, at the upper end of which is a bevel-wheel 11 (Fig. 3). This wheel meshes with another 15 bevel-wheel 12 secured to a short horizontal shaft 14 located at right angles to the plane of the platen 13, or to the plane of the work-piece located in the platen respectively. Owing to the connections described, the 20 shaft 14 is rotated in the same manner, as regards speed, as the control disk 6. It is provided with the known gripper supporting member 15 which swings or oscillates in the plane of the platen 13 and is opened 25 and closed in the usual manner.

In order to check the gripper supporting member 15 in the position of rest, a checking disk 16 is affixed to the shaft 14. The rim of this disk is provided with a plurality 30 of notches 17, of which there are four in the example shown corresponding to the number of the guide-ways in the disk 6. The notches co-operate with a checking bolt 19 which is under the pressure of a spiral 35 spring 18 and is controlled by a cam 20 suspended from the shaft 14 and acting on a roll 22 located on a pivot 23 extending laterally forth from the upper end of the checking bolt 19. The cam 20 is actuated by 40 means of a rod 21 (Fig. 4). The latter is moved to and fro, in the example shown in Figure 1, by a bell-crank lever 24—24^a, the arm 24^a of which is provided with a roll 25 engaging a cam-groove 3^a of the disk 3. 45 The shape of this groove is, of course, such that the movements of the members 24^a—24, 21, and 20 are timed in exact correspondence with the rotation and operation of the checking disk 16 for the grippers.

50 I wish it to be understood that the checking device shown and described is merely an example. It may be devised otherwise without departing from the invention. Also the gearing composed of the control disk 55 with its four guide-ways and of the disk or other member with the two rolls that co-operate with said guide-ways may be devised otherwise without departing from the invention. The conditions to be fulfilled 60 may be fulfilled by other, equivalent means. Such means may consist, for instance, of elliptical wheels, elliptical part-toothings, or the like.

65 Although I have shown the invention applied to a platen printing-press, I wish it to

be understood that I do not limit myself thereto, in that the invention can be used also in connection with printing presses of other kinds.

I claim:

1. An automatic feeding and discharging-device for printing-presses, especially platen printing-presses, comprising, in combination, gripper supporting members arranged for intermittent rotation on an axle located at right angles with respect to the plane of the work-piece; a rotary driving member and means to rotate it with uniform speed; another rotary member arranged to be driven by said driving member with alternately and gradually increasing and decreasing speed during every feed-motion of said gripper supporting members; and means to transmit positively motion from said driven member to the gripper supporting members.

2. An automatic feeding and discharging-device for printing-presses, especially platen printing-presses, comprising, in combination, gripper supporting members arranged for intermittent rotation on an axle located at right angles with respect to the plane of the work-piece; a rotary driving member and means to rotate it with uniform speed; another rotary member arranged to be driven by said driving member; motion-transmitting means provided at the driving member, and motion-receiving means provided at said driven member and being adapted to be engaged by said motion-transmitting means in such a way as to cause the driven member to rotate with alternately and gradually increasing and decreasing speed during every feed-motion of said gripper supporting members, the speed rising from zero to a predetermined maximum and falling from this to zero; and means to transmit positively motion from the said driven member to the gripper supporting members.

3. An automatic feeding and discharging-device for printing-presses, especially platen printing-presses, comprising, in combination, gripper supporting members arranged for intermittent rotation on an axle located at right angles with respect to the plane of the work-piece; a rotary driving member and means to rotate it with uniform speed; another rotary member arranged to be driven by said driving member; motion-transmitting means projecting forth laterally from said driving member; guide-ways provided in a side of the driven member and being adapted to be engaged by said motion-transmitting means, these latter being adapted to move along in said guide-ways alternately inwards and outwards; and means to transmit positively motion from the said driven member to the gripper supporting members.

4. An automatic feeding and discharging-device for printing-presses, especially platen printing-presses, comprising, in combination, gripper supporting members arranged for intermittent rotation on an axle located at right angles with respect to the plane of the work-piece; a rotary driving member and means to rotate it with uniform speed; another rotary member arranged to be driven by said driving member; a plurality of motion-transmitting means projecting forth laterally from said driving member; a plurality of practically radial guide-ways provided in a side of the driven member and being adapted to be engaged successively by the successive motion-transmitting means, these latter being adapted to be moved along in said guide-ways alternately inwards and outwards and thereby to rotate said driven member with a speed increasing from zero to a predetermined maximum, and decreasing from this maximum to zero; and means to transmit positively motion from the said driven member to the gripper supporting members.
5. An automatic feeding and discharging-device for printing-presses, especially platen printing-presses, comprising, in combination, gripper supporting members arranged for intermittent rotation on an axle located at right angles with respect to the plane of the work-piece; a rotary driving member and means to rotate it with uniform speed; another rotary member arranged to be driven by said driving member with alternately and gradually increasing and decreasing speed during every feed-motion of said gripper supporting members; means to transmit positively motion from said driven member to the gripper supporting members; and a checking device controlled by the printing-press and adapted to check the gripper supporting members in their position of rest.
6. An automatic feeding and discharging-device for printing-presses, especially platen printing-presses, comprising, in combination, gripper supporting members arranged for intermittent rotation on an axle located at right angles with respect to the plane of the work-piece; a rotary driving member and means to rotate it with uniform speed; another rotary member arranged to be driven by said driving member with alternately and gradually increasing and decreasing speed during every feed-motion of said gripper supporting members; means to transmit positively motion from said driven member to the gripper supporting members; and a checking device controlled by the printing-press and adapted to check the gripper supporting members and the actuating means connected positively with them in the position of rest of the said gripper supporting members.
7. An automatic feeding and discharging-device for printing-presses, especially platen printing-presses, comprising, in combination, gripper supporting members arranged for intermittent rotation on an axle located at right angles with respect to the plane of the work-piece; a rotary driving member and means to rotate it with uniform speed; another rotary member arranged to be driven by said driving member; motion-transmitting means provided at the driving member, and motion-receiving means provided at said driven member and being adapted to be engaged by said motion-transmitting means in such a way as to cause the driven member to rotate with alternately and gradually increasing and decreasing speed during every feed-motion of said gripper supporting members, the speed rising from zero to a predetermined maximum and falling from this to zero; and a checking device controlled by the printing-press and adapted to check the gripper supporting members in their position of rest.
8. An automatic feeding and discharging-device for printing-presses, especially platen printing-presses, comprising, in combination, gripper supporting members arranged for intermittent rotation on an axle located at right angles with respect to the plane of work-piece; a rotary driving member and means to rotate it with uniform speed; another rotary member arranged to be driven by said driving member; a plurality of motion-transmitting means projecting forth laterally from said driving member; a plurality of practically radial guide-ways provided in a side of the driven member and being adapted to be engaged successively by the successive motion-transmitting means, these latter being adapted to be moved along in said guide-ways alternately inwards and outwards and thereby to rotate said driven member with a speed increasing from zero to a predetermined maximum, and decreasing from this maximum to zero; means to transmit positively motion from the said driven member to the gripper supporting members; and a checking device controlled by the printing press and adapted to check the gripper supporting members and the actuating means connected positively with them in the position of rest of the said gripper supporting members.

In testimony whereof I have affixed my signature.

VIKTOR JERECZEK.
